Primary Examiner — Susan Moon Lee(74) Attorney, Agent, or Firm — Robert C. Montgomery; Montgomery Patent & Design(57) CLAIM

The ornamental design for an anchored outdoor pet dish, as shown and described.

DESCRIPTION

FIG. 1 is a perspective view of an anchored outdoor pet dish showing a dish portion and a base portion in assembly;
FIG. 2 is a top perspective view of the dish portion;
FIG. 3 is a bottom-front perspective view thereof;
FIG. 4 is a bottom-rear perspective view thereof;
FIG. 5 is a front view thereof;
FIG. 6 is a rear view thereof;
FIG. 7 is a left-hand side view thereof;
FIG. 8 is a right-hand side view thereof;
FIG. 9 is a top view thereof;
FIG. 10 is a bottom view thereof;
FIG. 11 is a perspective view of the base portion;
FIG. 12 is a front view thereof;
FIG. 13 is a rear view thereof;
FIG. 14 is a left-hand side view thereof;
FIG. 15 is a right-hand side view thereof;
FIG. 16 is a top view thereof; and,
FIG. 17 is a bottom view thereof.
